UNITED STATES PATENT OFFICE.

FREDERICK WESTERBECK, OF ST. LOUIS, MISSOURI.

CAN CLOSURE.

Application filed September 8, 1923. Serial No. 661,670.

To all whom it may concern:

Be it known that I, FREDERICK WESTERBECK, a citizen of the United States of America, a resident of the city of St. Louis, 5 in the State of Missouri, have invented certain new and useful Improvements in Can Closures, of which the following is a full, clear, and exact description, reference being had to the accompanying drawings, forming 10 a part of this specification.

This invention relates to improvements in can closures, and the novel features are especially adapted for use in a rotary closure having an operating member whereby it is 15 forced onto and removed from its seat. An object of the invention is to produce a simple and inexpensive closure of this kind having a strong connection uniting the closure and operating member. More specifically 20 stated, an object is to provide the simple device with interlocking elements through which the rotary thrusts are effectively transmitted from the operating member to the closure, and a separate attachment preventing separation of the interlocking 25 elements.

With the foregoing and other objects in view, the invention comprises the novel construction, combination and arrangement of 30 parts hereinafter more specifically described and illustrated in the accompanying drawings wherein is shown the preferred embodiment of the invention. However, it is to be understood that the invention comprehends changes, variations and modifications 35 which come within the scope of the claims hereunto appended.

As an illustration of a strong and simple form of the invention, I have shown a rotary closure member made of inexpensive sheet metal, and an operating member made of sheet metal interlocked with and soldered to the closure member. The operating member is formed with a large, smooth, non-circular 45 flange to be engaged by a person's fingers in tightening and loosening the rotary closure, the rotary thrusts being transmitted through the interlocking elements of the sheet metal members, and the solder being utilized to prevent unlocking of these interlocking elements.

Fig. I is a top view of a sheet metal can equipped with a sheet metal closure embodying the features of this invention.

Fig. II is a side elevation of the upper 55 portion of the can showing the closure thereon.

Fig. III is an enlarged vertical section showing the closure and a portion of the 60 neck of the can.

Fig. IV is a perspective view of the operating member of the closure.

Fig. V is a perspective view of the cylindrical closure member adapted to receive the 65 operating member.

A designates a sheet metal can adapted to contain ether and other highly volatile liquids, said can having a neck 1 provided with screw threads and a flange 2 turned inwardly and downwardly at the upper end 70 of the neck, as shown in Fig. III.

The closure comprises a sheet metal closure member B and an operating member C secured thereto. The closure member is a single sheet of metal having a cylindrical 75 portion 3 provided with screw threads conforming to the threads in the neck 1. This cylindrical member is closed at its upper end by means of a web 4 formed integral therewith.

The operating member C is a single sheet of metal comprising a web 5 larger than the web 4 and a non-circular flange 6 extending downwardly from the outer edge of web 5 and surrounding the upper portion of cylindrical member 3. The web 4 is circular but the web 5 is non-circular, and preferably square, so as to conform to the downturned flange 6 which is grasped by a person's hand to tighten and loosen the 90 closure. If desired a wrench can be applied to the flange, and one of my objects is to produce a closure of this kind strong enough to withstand considerable force in tightening the same, as it is somewhat difficult to securely confine volatile liquid, such as ether, in a container of this type. For this reason it has heretofore been customary to solder the tin closures directly to 95 tin cans containing ether.

However, the sheet metal closure herein disclosed is strong enough to withstand the severe rotary thrusts necessary to produce a tight seal, and after the can has been opened, the closure can be reused indefinitely to confine the ether.

I will now point out the manner in which the operating member C is associated with

the closure member to offer the necessary resistance to the severe rotary thrusts. A non-circular, preferably square, abutment 7 is formed integral with the closed end of the cylindrical member 3, and this abutment extends outwardly through an opening 8 in the web 5 of the operating member C. The walls of this opening surround and conform to the abrupt side faces of abutment 7, so as to cooperate therewith in preventing independent rotation of the operating member and closure member. These two thin sheet metal members are thus interlocked with each other in such a manner that the rotary thrusts are transmitted through and borne by the abutment 7, and the thin operating member is materially reinforced by its marginal flange 6 which provides the non-circular face for a wrench, or the like. 20 To prevent separation of the interlocking elements, a separate means is preferably employed to attach the operating member to the closure member. Fig. III shows solder 9 located around the abutment 7 and interposed between the inner margin of web 5 and the top of web 4. The solder can be conveniently applied in this manner to retain the abutment 7 in the web 5 of the operating member.

30 A disk 10 made of cork may be arranged within the closed end of the closure member and covered by a disk of varnished paper 11. The closure is thus provided with an internal yielding seat adapted to engage the annular top face of the can neck 1.

I claim:

1. A closure comprising a cylindrical closure member having a closed end and a non-circular abutment extending from said closed end, an operating member extending from said closed end and interlocked with said non-circular abutment to transmit rotary thrusts to said cylindrical closure member, and securing means whereby said members are united to prevent separation of the interlocking elements.

2. A closure comprising a cylindrical closure member having a closed end and an abutment formed integral with and extending from said closed end, an operating member extending from said closed end and interlocked with said abutment to transmit rotary thrusts to said cylindrical closure member, and solder whereby said members are

united to prevent separation of the interlocking elements. 55

3. A closure comprising a cylindrical closure member having a closed end and an abutment formed integral with and extending outwardly from said closed end, said cylindrical closure member and its closed end being made of a single piece of sheet metal, and a sheet metal operating member comprising a web and a non-circular marginal flange extending from the outer edge of said web, said abutment being interlocked with said web so as to transmit rotary thrusts from said operating member to said closure member, and said members being soldered to each other to prevent separation of the 70 interlocking elements.

4. A closure comprising a cylindrical closure member having a closed end and a non-circular abutment formed integral with and extending outwardly from said closed end, 75 said cylindrical closure member and its closed end being made of a single piece of sheet metal, and a sheet metal operating member comprising a web and a non-circular marginal flange extending from the outer edge of said web, said non-circular abutment being interlocked with said web so as to transmit rotary thrusts from said operating member to said closure member, and said members being soldered to each other to 80 prevent separation of the interlocking elements.

5. A can closure comprising a cylindrical sheet metal member provided with screw threads and having a closed end with an internal seat for the can to be closed, a non-circular abutment formed integral with said closed end and extending outwardly therefrom, and a sheet metal operating member comprising a web soldered to the outer face of said closed end and a non-circular marginal flange extending from the edge of said web and surrounding said cylindrical member, said web having a non-circular opening conforming to said abutment, and the side 100 faces of said abutment being surrounded by and adjacent to the walls of said opening so as to cooperate therewith in preventing independent rotation of said sheet metal members. 105

In testimony that I claim the foregoing I hereunto affix my signature.

FREDERICK WESTERBECK.
